REFRIGERATING APPARATUS

Donald H. Reeves, Dayton, Ohio, assignor to General Motors Corporation, Dayton, Ohio, a corporation of Delaware

Application August 15, 1940, Serial No. 352,748

2 Claims. (Cl. 211—153)

This invention relates to shelves and particularly to shelves for use in refrigerator cabinets.

Shelves heretofore employed in refrigerator cabinets have been constructed of ordinary iron or steel wires welded or bonded together and thereafter usually coated or plated with a metallic substance to enhance their appearance and to prevent corroding or rusting of the iron or steel. It has been found that in the use of such shelves, dishes or other receptacles slid back and forth thereon or in the case of shelves sliding within or upon supporting brackets the metallic coating is soon worn or scraped through to expose the iron and cause oxidation and rusting thereof. In fact the shelves of a refrigerator cabinet are usually the first parts thereof to show wear or to become unsightly from corrosion or rusting. I therefore propose the making of shelves of a non-oxidizing or non-rusting material but have encountered numerous difficulties in endeavoring to carry out my proposition. For example, stainless steel, which has a rather bright and desirable finish and which is substantially non-oxidizable, cannot be welded without destroying its non-corroding or non-rusting characteristics particularly at the welded points and therefore the use of stainless steel is not practical where a plurality of parts must be welded or bonded together to construct a shelf. Due to the strength and non-oxidizing characteristics of stainless steel it is a preferable material for use in refrigerators and my invention is therefore particularly directed to the making of a shelf for a refrigerator cabinet from such metal without the necessity of welding parts thereof together.

An object of my invention is to provide an improved shelf for a refrigerator cabinet and a novel method of making same.

Another object of my invention is to provide a shelf for a refrigerator cabinet that will be neat in appearance and will not corrode or rust even when surfaces thereof are scratched.

A further object of my invention is to provide a shelf for a refrigerator cabinet with a substantially flat, article supporting surface, and which shelf is made entirely by fitting various metallic parts together and thereafter pressing certain parts into interlocking or clamping engagement with certain other parts to provide a rigid unitary structure as distinguished from bonding or welding the shelf parts together.

In carrying out the foregoing objects it is a still further and more specific object of my invention to provide a strong and durable shelf formed of a plurality of stainless steel parts that are cut to

5 the desired length and bent into a predetermined shape to permit assembly thereof together by bending or pressing same into interlocking relation with one another to provide a rigid shelf structure.

Further objects and advantages of the present invention will be apparent from the following description, reference being had to the accompanying drawings, wherein a preferred form of the present invention is clearly shown.

In the drawings:

Fig. 1 is a top plan view of a shelf constructed in accordance with the present invention;

Fig. 2 is an enlarged vertical transverse sectional view of the shelf shown in Fig. 1 and is taken on the line 2—2 of Fig. 3;

Fig. 3 is an enlarged fragmentary horizontal sectional view of the shelf taken on the line 3—3 of Fig. 2;

Fig. 4 is an enlarged vertical sectional view of the rim of the shelf at the intersection of a reinforcing member and is taken on the line 4—4 of Fig. 2;

Fig. 5 is a view similar to Fig. 4 and is taken in front of the reinforcing member on the line 5—5 of Fig. 2;

Fig. 6 is a fragmentary sectional perspective view of a rim portion of the shelf before parts thereof are bent into the desired interlocking form;

Fig. 7 is a top plan view of a modified form of shelf constructed in accordance with this invention;

Fig. 8 is an enlarged horizontal fragmentary sectional view of the shelf shown in Fig. 7 and is taken on the line 8—8 of Fig. 9;

Fig. 9 is a vertical sectional view through the front rim of the shelf and is taken on the line 9—9 of Fig. 8;

Fig. 10 is a sectional view through one corner of the shelf taken on the line 10—10 of Fig. 8;

Fig. 11 is a sectional view through the side rim of the shelf taken on the line 11—11 of Fig. 8;

Fig. 12 is a fragmentary sectional perspective view of a reinforcing member for the modified form of shelf shown in Fig. 7; and

Fig. 13 is a fragmentary perspective view taken in a direction toward one front corner of the shelf.

Referring to the drawings, for illustrating my invention, I have shown in Fig. 1 thereof a food supporting shelf generally represented by the reference character 20 and adapted to be located in the refrigerated chamber or compartment of a refrigerator cabinet. Shelf 20 includes a

bounding rim forming the front, and two sides of the shelf. The bounding rim is composed of an inner bounding frame member 21 and an outer bounding frame member or means 22 (see Fig. 2) both of which are formed of approximately .031 of an inch thick stainless sheet steel. Outer bounding frame means or member 22 of the shelf rim is of one piece construction having its ends abutting one another as at 23 (see Figs. 1 and 3) at the back of the shelf 20. The inner frame member 21 is also of one piece construction with its ends not joined but abutting one another as at 24 (see Figs. 1 and 3) at the front of the shelf 20. Inner frame member 21 has its bottom edge rolled or reversely bent over to provide a bead-like portion 26 thereon. The outer frame member 22 has a cross-sectional contour of the shape shown in Fig. 6 of the drawings prior to its deformation in assembling parts of the shelf, and includes a straight vertical portion 27, outwardly bent or rolled upper and lower portions 28 and 29 respectively and laterally extending horizontally disposed portions 31 and 32 for a purpose to be presently described. A plurality of equally spaced apart slots 33 extend downwardly from the top edge of the inner frame member 21 and a plurality of similarly spaced apart slots 34 extend inwardly of the edge of the top horizontally disposed portion 31 of the outer frame member 22. The slots 33 and 34 are located along the sides only of the shelf 20 and are adapted to register with one another for a purpose to be presently described. A plurality of wires 36 reversely bent as at 37 (see Fig. 1) extend from one side to the other side of the shelf 20 to provide a reticulated flat food supporting surface. The reversely bent end portion 37 of wires 36 extend parallel with the side of shelf 20 and fit into the hollow bead at the top of frame means or bounding member 22 provided by the rolled over portion 28. Wires 36 are also preferably cut and preformed of substantially .094 of an inch diameter stainless steel round stock. A brace, generally represented by the reference character 38 (see Fig. 1), extends from the front to the back of shelf 20 and comprises an approximately .031 of an inch thick strip of stainless steel preformed or bent upon itself as at 39 (see Fig. 2) and further bent as at 41 and 42 to provide outwardly and thence upwardly extending portions. The strip of brace 38 has its ends cut away as at 43 (see Figs. 4 and 5) and is provided with legs 44 (see Figs. 2 and 3) extending laterally therefrom. Legs 44 abut against the inner face of frame member 21 and are secured to shelf 20 in a manner to be hereinafter described. The upwardly extending spaced apart portions 42 of the strip of brace 38 are provided with a plurality of spaced apart slots 46 (see Fig. 5) for the reception of the wires 36. A cap or cover 47 of approximately .021 of an inch thick stainless steel is disposed over the strip of brace 38 to close the gap between the upwardly extending portions 42 thereof. This cap or cover 47 has depending side portions 48 provided with spaced apart slots 49 (see Fig. 5) for receiving the cross wires 36 and which portions 48 are bent under the outwardly extending parts 41 of the brace strip to lock the cap in position on the brace. The bottom horizontal portion 32 of outer frame member 22 has a part thereof cut out as at 51 (see Fig. 2) and the top horizontal portion 31 of frame member 22 has a part thereof cut out as at 52 (see Fig. 2) for the reception

of the end portions of brace 38. As stated the outer frame member 22 of the rim of shelf 20 is preformed into the shape disclosed in Fig. 6 of the drawings to permit assembly of the various parts of the shelf before the same is crimped or bent over the edges of the inner frame member 21.

In assembling parts to form shelf 20 the preformed rectangular-shaped outer frame member 22 having the cross-sectional contour as shown in Fig. 6 of the drawings and having its end abutted as at 23 is spread apart at its ends to permit insertion into the frame of the preformed wires 36. The wires 36 are moved toward the front edge of the shelf into position within the rectangular frame with their reversely bent end portions 37 fitting within the hollow bead of the outer frame member 22, provided by the rolled or bent portion 28 thereof. The preformed rectangular-shaped inner frame member 21 having the predetermined cross-sectional contour as shown in Fig. 6 of the drawings is then placed within the frame member 22. In order to locate member 21 within member 22 one end of frame member 21 is placed against the inner surface of frame member 22 at a diagonally opposite corner of the shelf bounding rim from the ends of frame 22. The reversely bent bottom edge of frame member 21 is pushed into the hollow bead of frame member 22, provided by the rolled or bent portion 28 thereof, and the walls of slots 33 in frame member 21 fit around the wires 36 and space these wires the proper distance apart. The process of pushing frame member 21 into place within the frame member 22 is started at one end of the member 21 and is continued around the bounding rim of the shelf until its ends are aligned and abutted as at 24 at the front of the shelf. Thereafter the preformed strip 39 of brace 38 is placed within the rectangular bounding rim with its legs 44 against the inner vertical portion of frame member 21. After the cap or cover is placed over strip 39 and wires 36 the depending side portions 48 thereof are pressed inwardly around the bent portions 41 of strip 39 to lock the cross wires together at the center of the shelf 20. Horizontal projections 31 and 32 of frame member 22 are bent inwardly by a press or other suitable tool against the inner vertical wall of frame member 21 about the periphery of the shelf to rigidly clamp the various parts thereof together into the unitary shelf structure 20. The projections 31 and 32 in addition to securing the frame members 21 and 22 together also clamp the legs 44 of brace 38 to the shelf structure.

In Fig. 7 of the drawings I have shown a modified shelf structure generally represented by the reference character 60 having cross wires extending parallel with the sides of the shelf instead of parallel with the front and back of the shelf as is the case of shelf 20. Shelf 60 comprises a rectangular bounding rim 61 made of flat strip-like stainless steel and preformed so as to have a substantially U-shaped cross sectional contour prior to bending operations to be performed thereon. Bounding rim 61 forms a front 62, sides 63 and back 64 of the shelf 60 and has its ends abutted as at 66 (see Fig. 8) but not integrally joined together. The substantially U-shaped cross sectional contour of rim 61 comprises a straight vertical wall portion 67 and upper and lower horizontal wall portions 68 and 69 respectively (see Fig. 9). Along all sides of rim 61 the outer edge of the wall portions 68 and 69 are bent as at 71 and 72 while the wall portions 68 and 69

at the four corners of the rim are flat or unbent. The rectangular-shape and cross sectional contour of rim 61 thus far described and as shown in Fig. 13 of the drawings is its preformed character and is so preformed as to permit assembly of various parts of the shelf together. Vertical wall portion 67 of rim 61 is provided with a plurality of equally spaced apart holes 74 (see Fig. 8) which receive individual round stainless steel cross wires 76 having their end portions preformed or bent in opposite directions to one another as at 77 and 78. The holes 74 are of a greater diameter than the wires 76 and permit the end portions 77 and 78 of the wires, when held at approximately 45° angle with respect to the front and back of shelf 60, to be inserted into the openings 74 and thereafter moved into the right-angled position, as shown in Fig. 8 of the drawings, relative to the front and back of the shelf. After cross wires 76 are assembled in place upon rim 61 a metal insert 81, having a cut-away corner portion 82 (see Fig. 9), is pushed from a corner of the rim into the front edge thereof to hold the ends 78 of wires 76 in a parallel position relative to rim 61 by virtue of these ends of wires 76 being locked in the cut-away part 82 of the insert 81. A similar insert is installed in back edge 64 of rim 61 in the same manner to lock the end portion 77 of wires 76 to the back of the shelf 60. Since the wall portions 68 and 69 at the corners of rim 61 are open or are not bent as at 71 and 72 along the sides of the rim the metal inserts may be assembled through these corners and such inserts increase the structural strength of the shelf. A metal insert 83 is also pushed from an open corner of the rim 61 into each of the sides 63 of the rim. The inserts 83 may be of the same cross sectional shape and character as the inserts 81 and they may be constructed of stainless steel. However, since this material is expensive another more inexpensive material may be employed in the making of the inserts and a cover or facing member can then be placed over the exposed portion of the inserts intermediate the portions 71 and 72 of the rim 61. For example, the stainless steel inserts 81 and 83 are shown in Fig. 11 of the drawings as being exposed intermediate the bent edge portions 71 and 72 of walls 68 and 69 while in Fig. 9 the exposed portion of insert 81, particularly at the front of shelf 60, is provided with a relatively thin cover 84 thereover and which cover is clamped between the bent portions 71 and 72 and the insert. Cover 84 may be of any suitable or desirable material and, since it is exposed when the refrigerator cabinet door is opened, it may be colored to match other trim members or portions of the cabinet. It will be noted that the portion of insert 81 at the front of shelf 60 intermediate the bent lips 71 and 72 of rim 61 projects outwardly beyond these lips to render the coloring arrangement of the cover 84 more prominent to bring out the color trim scheme of the refrigerator cabinet.

After the inserts 81 and 83 are located within rim 61 of shelf 60 curved elbow-like insert members 85 (see Figs. 8 and 10) are placed between the wall portions 68 and 69 at the four open corners of the rim. Thereafter the edges of these wall portions at the shelf corners are bent or pressed over the inserts 85 in any suitable or convenient manner to correspond to the bent-over edge portions 71 and 72 to thereby firmly clamp the corner inserts 85 in place. Insert members 85 may be molded from any suitable plastic or the like material and when abutted against the other inserts 81 and 83 of the rim

provide a relatively solid bounding rim of increased structural strength over the strength afforded by the thin stainless steel shelf parts. The elbow corner inserts 85 may be provided with a tapering projecting portion 86 to meet and carry the colored projection 84 at the front of the shelf around the front corners thereof. A brace, generally represented by the reference character 87, extending across the wires 76 of shelf 60 comprises a strip of stainless steel 88 folded or bent upon itself as at 89 (see Fig. 12) and further bent to provide outwardly extending horizontal portions 91 and upwardly projecting portions 92. The projections 92 are provided with spaced apart slots (not shown) extending downwardly from their top edges for the reception of the cross wires 76. A cap or cover 93 of thin stainless steel is placed over the brace 87 and has legs 94 slotted as at 95 for receiving the cross wires 76. The lower edge portion of the legs 94 is bent around the horizontal portion 91 of strip 88 as at 96 to clamp the cap or cover 93 to the brace 87. Each end of the cap or cover 93 is provided with a normally flat extending portion 97 which is bent around a cross wire 76 adjacent the side of the rim 61. The brace 87 maintains the central portions of cross wires 76 in proper spaced apart relation to one another and increases the structural strength of shelf 60 in that it causes weight placed upon one portion of the shelf to be distributed to other portions of the shelf through the various cross wires.

From the foregoing it will be seen that I have constructed a shelf or shelves from relatively thin metal parts which parts are secured together in such interlocking manner that the shelf is substantially as strong as other shelves wherein the parts are welded or bonded to one another. The construction and method of interlocking frame members, braces, and wires together as herein disclosed provides improved shelves that are flat and strong and made entirely of preformed stainless steel elements secured together without soldering or welding the elements. This the shelves disclosed have a finish which remains bright over long periods of time and are characterized by their non-oxidizing or non-rusting properties even when surfaces of parts thereof become scratched. The shelves disclosed are assembled from preformed or partially preformed parts by bending and pressing operations which are simple and relatively easy to carry out in mass production. Interlocking of the bent end portions of the article supporting wires of the shelves disclosed against the sides of the shelf bounding members greatly strengthens the shelf structure and maintains same relatively flat in that the bent end portions of the cross wires tends to prevent twisting of the shelf.

While the form of embodiment of the invention as herein disclosed, constitutes a preferred form, it is to be understood that other forms might be adapted, all coming within the scope of the claims which follow.

What is claimed is as follows:

1. A shelf for disposition in a refrigerator cabinet comprising, two vertically disposed sheet metal members interlocked together and each extending continuously around four sides of an open area to provide a bounding frame therefor, a plurality of spaced apart round members extending in one direction only across the open area bounded by said frame to provide the shelf with an article support, all of the spaced apart round

members intermediate the sides of said frame being separate therefrom and extending between two opposed sides thereof, and all of the spaced apart round members extending across the open area defined by said frame being substantially parallel to one another and disposed in the same horizontal plane to provide said article support with a flat surface, said round cross members having their end portions bent and interlocked between the two sheet metal members of said frame to cooperate with the sides thereof adjacent the said opposed sides for preventing twisting of the shelf structure.

2. In a shelf for disposition in a refrigerator

5 cabinet comprising, two sheet metal members interlocked together and each extending continuously around four sides of an open area to provide a bounding frame therefor, a plurality of substantially parallel spaced apart members extending across the open area bounded by said frame to provide the shelf with an article supporting surface, and said spaced apart cross members having their end portions bent, said bent portions being clamped between said sheet metal members and cooperating therewith to prevent twisting of the shelf structure.

DONALD H. REEVES.
